UNITED STATES PATENT OFFICE.

EMIL BÖSEBECK, OF BARMEN, AND EUGEN TÜRCK, OF LANGERFELD, NEAR BARMEN, GERMANY.

METHOD OF PRODUCING LEAFLIKE FIGURE WORK IN BRAIDED LACE.

Application filed August 26, 1921. Serial No. 495,724.

(GRANTED UNDER THE PROVISIONS OF THE ACT OF MARCH 3, 1921, 41 STAT. L., 1313.)

To all whom it may concern:

Be it known that we, EMIL BÖSEBECK and EUGEN TÜRCK, both citizens of the German Republic, residing at Barmen, Germany, 5 and Langerfeld, near Barmen, Germany, respectively, have invented certain new and useful Improvements in a Method of Producing Leaflike Figure Work in Braided Lace (for which we have filed applications 10 for patent in Germany, October 29, 1919, Patent No. 341,246; England, October 29, 1920, Patent No. 153,266; France, November 10, 1920; Belgium, October 26, 1920; Italy, October 27, 1920; Holland, November 9, 15 1920; Switzerland, November 6, 1920; Spain, October 30, 1920; Austria, February 5, 1921; Poland, February 19, 1921; Czechoslovakia, March 30, 1921), of which the following is a specification.

20 In the manufacture of braided lace on single thread braiding machines leaf-like figure-work has hitherto been produced as follows: At the particular places, either several longitudinal threads are held together, like the warp threads of a weave, by means of a further thread extending, like a weft thread, in a zigzag line across this part of the fabric, and so forming a weave-like element in the latter, or a tight braid- 25 work is produced around two or more longitudinal holding threads by means of several braiding threads directed to and fro and coming in part from the right and in part from the left. Also two figures of the first 30 described kind have been joined at the ends by braiding their threads together, whereby a real leaf figure does not result but a figure broken away in the middle. All these 35 methods of manufacture require great length of pattern strip, so that in the formation of said figure-work the production of the machine is considerably reduced. Moreover with these methods it is very difficult to obtain an actual leaf-like form in the figure- 40 45 work since these elements in the fabric are usually too tightly drawn together and thus too narrow in the middle, but towards the ends the gradual narrowing is not obtained.

Now the subject matter of our invention 50 is a new method of producing such leaf-like figure-work by which method the above-described drawbacks are quite obviated. By this method two or more pairs of special

longitudinal, juxtaposed threads serve for producing the leaf-like figures, which 55 threads are held together in the manner of a weave by other threads constituting the groundwork and running diagonally through this, and of which the one pair is worked in under strong tension and remains 60 always in the middle of the leaf-like figure while the remaining threads distributed on both sides of the first pair, are worked in under lighter tension and, during braiding, interchange their positions with respect to 65 the middle pair between the separate leaf-like figures, so that the individual lightly-tensioned threads become located in the one leaf on the one side, and in the next leaf on the other side, of the middle pair of 70 threads.

This new method necessitates no special lengthening of the pattern strip so that by employing said method the production of the machine is not diminished. Moreover by 75 this method the figure-work obtains faultless leaf formation, since the lateral pairs of longitudinal threads readily become bowed out in the figures owing to their light tensioning and their change of position 80 between each two figures, and so yield the leaf form. In order to allow these figures to be specially prominent in the lace, the said longitudinal threads may be thicker 85 than the remaining braiding threads, at least if they do not come into use for the formation of other parts of the web.

The new method is explained by the example of a manner of carrying out same shown in the accompanying drawing, where- 90 in—

Fig. 1 shows a piece of lace, of about actual size, produced by adopting the method, and

Fig. 2 shows diagrammatically on a 95 larger scale two leaf-like figures produced according to the invention.

According to Fig. 1 the braided lace produced as an inset contains two series *a* and *b* of leaf-like figures *c*, these series running 100 zig-zag and intercrossing. According to the invention the figure-work is formed by means of three pairs of longitudinal threads *d*, *d*¹, *e*, *e*¹, and *f*, *f*¹, (Fig. 2) which pass through the entire series of figures. The 105 pair *d*, *d*¹ always remains in the middle of

the figures. The pair d, d^1 is worked in with a strong tension and these threads d, d^1 therefore have an approximately straight course in the several figures c . The two other pairs, e, e^1 , and f, f^1 , of threads are disposed each at one side of the first pair. When the braided work is produced, these two pairs are given a lighter tension and interchange their positions with respect to 10 the middle pair d, d^1 at places between the separate figures, the said two pairs being braided with the middle pair and with each other in such manner that at these places the six threads are firmly drawn together. 15 As is specially observable from Fig. 2, between the said places these lateral pairs of threads obtain a bowed-out form, since they are under less tension than the middle pair. In the leaf-like figures the six threads d, d^1, e, e^1, f, f^1 are held together in the manner of a weave by means of the threads g . The latter are the usual braiding threads of the groundwork and traverse the latter in the diagonal direction. These threads g can 20 always be changed and taken just as the character of the groundwork presents them at the particular place.

Obviously the leaf-like figures do not need to be connected directly with one another. 30 They can also be spaced apart in which case the various aforesaid pairs of threads can be used between them for forming other figure-work.

I claim:—

35 1. The method of producing leaf-like figure-work in braided lace which comprises forming each leaf by braiding together a plurality of longitudinal threads by means of a plurality of groundwork threads each

of which only once crosses each of said longitudinal threads and causing the outer longitudinal threads to intercross at either end of the leaf so as to change sides, a leaf like figure being formed as a continuation of the first after the intercrossing of the longitudinal threads. 40

2. The method of producing leaf-like figure-work in braided lace which comprises forming each leaf by braiding together a plurality of differently tensioned longitudinal threads by means of a plurality of groundwork threads crossing said longitudinal threads and causing the outer longitudinal threads to intercross at either end of the leaf so as to change sides a leaf like figure being formed as a continuation of the first after the intercrossing of the longitudinal threads. 45

3. As a new article of manufacture, braided lace, comprising leaf-like figure work surrounded by groundwork, each leaf consisting of a plurality of longitudinal threads and a plurality of groundwork threads, each of which crosses only once and interconnects said longitudinal threads, the outer longitudinal threads intercrossing at either end of the leaf so as to change sides, said intercrossing threads forming a leaf like figure as a continuation of the first. 50

In testimony whereof, we affix our signatures in the presence of two witnesses.

EUGEN TÜRCK.
EMIL BÖSEBECK.
